TOY GRADING MACHINE

William Meredith Arnold, Jr., Hernando, Miss.

Application June 21, 1951, Serial No. 15,627

Term of patent 14 years

(Cl. D34—15)

To all whom it may concern:

Be it known that I, William Meredith Arnold, Jr., a citizen of the United States of America, residing at Hernando, in the county of De Soto and State of Mississippi, have invented a new, original, and ornamental Design for a Toy Grading Machine, of which the following is a specification, reference being had to the accompanying drawing, forming a part thereof, wherein:

Figure 1 is a side elevation of a toy grading machine, showing my new design.

Figure 2 is a top plan of the same.

Figure 3 is a rear elevation of the same, and

Figure 4 is a front elevation of the same.

I claim:

The ornamental design for a toy grading machine, substantially as shown.

WILLIAM MEREDITH ARNOLD, JR.
